PUSHBUTTONS

Theodore G. Pichel, Sunnyvale, Calif., assignor to
Hewlett-Packard Company, Palo Alto, Calif., a
corporation of California

Filed Mar. 1, 1963, Ser. No. 262,013
4 Claims. (Cl. 116—124)

This invention relates to a pushbutton which may be mounted on a pushbutton-switch so as to provide a visual indication when in a depressed or actuated position. Its principal object is to provide a low cost, simple, and reliable pushbutton which becomes luminescent and readily discernible when actuated.

In the drawing,

FIGURE 1 is a half sectional view of the pushbutton assembly when in an actuated position;

FIGURE 2 shows the face of the pushbutton when actuated;

FIGURE 3 shows a cut-away view of the pushbutton assembly when not actuated;

FIGURE 4 shows the face of the pushbutton when not actuated;

FIGURE 5 shows the construction of the luminescent assembly of the pushbutton;

FIGURE 6 shows a sectional view of the pushbutton of FIGURE 1 taken along the line B—B;

FIGURE 7 shows a top view of the luminescent assembly of FIGURE 5;

FIGURE 8 shows a perspective view of the pushbutton; and

FIGURE 9 shows an exploded view of the pushbutton.

Referring to the drawings, there is shown a pushbutton assembly comprising an outer casing 12 with an aperture 14 therein. A character plate 16 with a translucent number or indicium on its face is fixedly mounted at the aperture 14 and fixedly held in place by a plug-like inner element 18 which is fixedly fitted into the outer casing 12. This plug-like inner element 18 has a cavity 22 located adjacent to the aperture 14. The inner element 18 also has two holes 27 which extend therethrough between the cavity 22 and the end of the inner element 18 which is remote from the aperture 14. A luminescent assembly 20, constructed as shown in FIGURES 5 and 7, is slidably positioned within the cavity 22 of the inner element 18. The luminescent assembly 20 includes a supporting element or plate 24 with two pins 26 attached thereto. The supporting plate 24 is mounted in the cavity 22 by means of the pins 26. These pins 26 extend through the holes 27 provided in the inner element 18 and protrude at the end which is remote from the aperture 14. A spring 30 is positioned longitudinally between the character plate 16 and the surface of the supporting plate 24 which is remote from the pins 26. A resilient cushion 32 made of polyurethane foam is fixed to the surface of the supporting plate 24 on which the spring 30 bears. The surface 34 of the resilient cushion 32 which is opposite the supporting plate 24 is made luminous with luminescent paint or by fixing luminous paper thereto. The cushion 32 starts to compress only after substantial compression of the spring has brought the surface 34 in close proximity to the aperture 14. When the pushbutton is depressed or actuated, as shown in FIGURE 1, by pushing inward the pins 26 the spring 30 is compressed and the translucent character

2

36 of the character plate 16 comes into direct contact with the luminescent surface 34 causing the character 36 to appear luminous, as shown in FIGURE 2. When the pushbutton is de-actuated, as shown in FIGURE 3, the spring 30 expands moving the character plate 16 away from the luminescent surface 34 causing the character 36 to appear non-luminous, as shown in FIGURE 4. The translucent character 36 causes enough reflection of external light to prevent clearly seeing the luminescent surface 34 when the pushbutton is de-actuated. When the pushbutton is used with a pushbutton switch, it is fixedly mounted on the shaft or plunger of the pushbutton switch with the pins 26 abutting upon a reference surface such as a switch panel for both the actuated and de-actuated positions shown in FIGURES 1 and 3. The pushbutton is depressed to actuate the pushbutton switch. For the depressed pushbutton position corresponding to the actuated position of the pushbutton switch the luminescent surface 34 is in direct contact with the character plate 16 as shown in FIGURE 1. The resilient cushion 32 provides the play necessary to permit the pushbutton to be subsequently further depressed to de-actuate the pushbutton switch.

I claim:

1. A pushbutton comprising:
an outer casing having an aperture at one end thereof,
an indicating plate fixedly mounted at said aperture and
having a translucent indicium,
a supporting plate slidably mounted within said outer
casing and supporting a layer of visually contrasting
material,
pin-like means connected to said supporting plate to
move said supporting plate with respect to said outer
casing whereby said layer of visually contrasting
material moves toward the translucent indicium of
said indicating plate, and
a first resilient element for retracting said supporting
plate away from said indicating plate.
2. A pushbutton as in claim 1 including:
a second resilient element between said supporting plate
and said layer of visually contrasting material,
said second resilient element starting to compress only
after substantial compression of said first resilient
element.
3. A pushbutton as in claim 2 wherein said layer of
visually contrasting material is luminous.
4. A pushbutton as in claim 2 wherein:
said first resilient element is a spring; and
said second resilient element is a cushion.
